MACHINE FOR GENERATING GEARS

Heinrich Schicht, Huckeswagen, Germany, assignor to firm: W. Ferd. Klingelnberg Söhne, Remscheid-Berghausen, Germany

Application July 18, 1936, Serial No. 91,416
In Germany February 16, 1934

9 Claims. (Cl. 90—4)

This invention relates to a method of and a machine for generating gears, and more particularly gears having longitudinally curved teeth.

In certain known processes of manufacturing bevel gears, the teeth are cut by spiral or helicoidal cutters, as the tool and work are caused to roll upon each other, and the tool is swung about the center of the imaginary crown gear meshing with the gear being cut. In such processes, the number of tangential cuts which can be taken is limited to the cutting teeth engaged in the milling process, and teeth having faces of excess width are generated by the tangential cuts, and must be polished in order that they may run smoothly. This excess width necessitates a prolonging of the lapping operation in the case of hardened gears.

The object of the present invention is to avoid the disadvantages of the prior processes and to materially reduce the manufacturing time. Briefly stated, the improved process consists in subjecting the cutting tool to an additional rectilinear displacement in the plane of the crown gear, without changing the inclination of the tool axis with respect to the crown gear plane, as the cutting tool and the work roll upon each other, and the tool is swung about the crown gear center. The cutting tool cuts a width of tooth which is in excess of the distance corresponding to the length of the tooth, and prior art disadvantages of using helicoidal cutters are done away with.

In view of this action, the cutter can be greatly reduced in length, and hence disc-shaped cutters can be employed. Use of a disc-shaped tool which is swung round the center of the crown gear permits simple and most exact positioning and guiding of the tool during its cutting motion. This is in strong contrast to known processes in which disc-shaped tools must be actuated by steel bands or by tooth segments, and in which the machine elements must be changed for each new gear ratio or cone angle so that a very large stock of generating rolling cones must be kept available. The prior art devices also failed to offer sufficient resistance to cutting pressure to attain any high degree of efficiency.

All of the prior art disadvantages are overcome by the present invention. This invention will be understood when the following description is read in conjunction with the accompanying drawings in which:

Fig. 1 is a diagram showing a short, spiral cutter or cone grinding worm in the process of cutting curved teeth on a bevel gear;

Fig. 2 is a view similar to Fig. 1, but showing the cutting tool as a cylindrical worm;

Fig. 3 is a diagram showing a short or disc-shaped cutter in the process of cutting curved teeth on a bevel gear, the tool displacement being coincident with the line of contact between the tool and the crown gear plane;

Fig. 4 is a fragmental section showing the shape of the teeth of the tool in Fig. 3;

Fig. 5 is a view similar to Fig. 3, but with the direction of tool displacement inclined with respect to the line of contact between the tool and the crown gear plane;

Fig. 6 is a longitudinal section, partly diagrammatic, through a milling machine suitable for use in producing gears according to the method of the present invention;

Fig. 7 is a fragmentary sectional view of the dividing head used with the machine shown in Fig. 6;

Fig. 8 is a fragmentary sectional view of the compensating mechanism employed in the machine of Fig. 6 for maintaining correct relation between the work and the tool;

Fig. 9 is a face view of the cutting tool face plate showing a cylindrical cutter in the process of cutting a spur gear;

Fig. 10 is a view similar to Fig. 9 showing a conical cutting tool in the process of cutting a bevel gear; and

Fig. 11 is a view similar to Figs. 9 and 10, but showing a cylindrical cutting tool in the process of cutting curved teeth on a stationary spur gear.

Referring to Fig. 1 of the drawings, the reference character *a* represents a bevel gear having curved teeth in the process of being cut by a conical cutter *b*. This cutter, as shown, is of such a size that its cone or mantle extends over a portion of the tooth width on the gear being cut and performs three movements as follows:

1. A cutting movement designated by arrow *c* and consisting of rotation of the cutter on its own axis in engagement with the work.

2. A rolling movement indicated by the arrow *d* and caused by swinging the cutter about the point *O* designating the center of the imaginary crown gear.

3. A rectilinear movement, designated by the double arrow *d*, in the direction of the line of contact between the cutter and the crown gear plane on a straight line touching a circle concentric with the crown gear center *O*.

As shown by the double arrow *d* (Figs. 1, 2 and 3) the supplementary tool movement may be performed by the tool once while it makes a com-

20

30

30

40

40

55

plete trip around the crown gear center in engagement with the work, or it may reciprocate several times. The three tool movements also regulate the rotation of the work.

5 Rotation of the work is caused by engagement with the tool and from the swing of the tool about the center of the crown gear, this latter movement always producing the same direction of work rotation. In addition, the supplementary 10 tool displacement during a change in its direction produces its effect. If this latter displacement is in such a direction as to supplement the first two movements, it speeds up the rotation of the work, but if this displacement opposes the 15 other two movements then the speed of rotation of the work is reduced. In the exterior limit position the outside diameter of the cutter must at least touch the outside diameter of the gear, or preferably, project over it. In the interior 20 limit position, the inner diameter of the cutter must touch the inner diameter of the gear or project over it slightly.

The supplementary tool displacement above mentioned has a marked advantage, in that a 25 greater number of tangential cuts may be obtained in the direction of the tooth length, and caused by the edges of the cutting teeth continuously taking up different positions in the direction of the double arrow *d*. The more often this 30 displacement occurs, the more perfect is the tooth formation. Consequently, when practicing this method, one is not dependent upon the number of cutting edges on the tool. If it is desired to use a shorter cutter, a disk-shaped cutter 35 of the type shown in Figs. 3, 4 and 5 may be employed.

When a disk-shaped tool is employed, the cutting must be carried out as a single step process, although the supplementary tool movement characterizing the new process remains the same. 40 This movement is, however, increased so that the disk-shaped tool covers the whole tooth width and travels in the direction indicated by the arrow *d* in Figs. 3 and 5, at least between the 45 limits designated A and C in Fig. 3.

In Fig. 3 the supplementary displacement of the tool is in the direction of its line of contact with the crown gear plane. In Fig. 5 this displacement is at an angle to the line of contact 50 with the crown gear plane. By varying this angle a change in tooth curvature may be obtained. For example, in a process according to Fig. 3, a large spiral angle with a sharp curvature is desirable, in order to obtain sufficient 55 covering with a small number of teeth and tooth widths. However, for large tooth widths and great pitch pressures a smaller spiral angle with a decrease in axial pressure is desirable. An example of this latter is given in Fig. 5.

60 A machine for generating gears according to the method above described, is illustrated in Fig. 6 of the drawings. In Fig. 6 reference character 1 designates the cutter mounted on a tool spindle 2 and adapted to be driven by a motor 3 through 65 suitable gearing which will be described later. The work 4 is carried on a work spindle 5 also driven by motor 3 over a bevel gear drive 6, 7 connected to main shaft 9.

The drive for producing rolling and generating 70 motion of the cutter 1 in the ideal crown gear is transmitted from shaft 9 through spur gearing to a worm wheel 10 on face plate cylinder 11. This cylinder turns on the horizontal axis 9.

On the front face of cylinder 11 adjacent the 75 work, is a slideway 12 which can be rotated on a

journal 13, the axis of this journal being eccentric and lying parallel to the central axis of the face-plate cylinder 11. Mounted in slideway 12 and guided therein is a carriage 14 which can be moved by means of a threaded spindle 15 connected with the machine drive. A tool support 16 is mounted on the carriage 14. This carriage makes it possible for the tool to perform the supplementary movement indicated by the double arrows *d* in Figs. 1 and 2, and which is 10 characteristic of this invention.

The carriage 14 is displaced by a piston 17, operated by oil pressure from a pump of known type and controlled by a valve, also of known type. The number of up and down strokes of 15 the piston 17 can be regulated as desired, and is dependent upon the oil pressure and the cutting resistance offered to the tool. As the reciprocating movement, already described, is controlling the rolling and generating movement, 20 the piston 17 acts on a rack on the casing of a differential 18 on shaft 19. Fixed on the casing of differential 18 is a spur gear 20 connected by change gears 21 and 22 with the rim of gear wheel 23. Gear wheel 23 revolves around the 25 face-plate cylinder 11 and transmits the turn of the differential over the spur gears 23—26, and bevel gears 27 and 28 to the threaded spindle 15. The supplementary turn of the work corresponding to this turn of the differential is transmitted 30 along the parts of the drive 29, 30, 42, 43 and 45. If a short movement is desired when cutting, then the drive is transmitted from the differential worm shaft 31, over change gears 32, 33, 34, 35, 36, bevel gears 37 and 38, spur gears 39 and 36 26 (Fig. 9) and bevel gears 22 to 28, to spindle 15. This spindle moves the carriage 14 on which the cutter revolving face-plate is mounted.

When a disk-shaped cutter is used, any well known type of dividing head may be connected 40 to the shaft 40 (Fig. 7) by a coupling 41. This dividing head serves to index the work from tooth to tooth after each forward and return stroke of the cutter on the slideway 12.

The dividing head shown in Fig. 7 may be 45 thrown into gear by disconnecting bevel gear 43 from shaft 42 and connecting gear 44 to shaft 40 by moving the coupling 41 from left to right in Fig. 7. In addition to this, the change gears 45, 46 and 47, Figs. 6 and 7, are dismounted, and the dividing worm connected to shaft 40 by change gears 48 and 49, one only being shown in Fig. 8.

With the above substitutions made, rotation of shaft 51 caused by either differential 50 or 18 55 is transmitted along the casing 52 (Fig. 7), pawl 53, dividing plate 54 to shaft 40, and then through change gears 48, 49 and worm gear 55, 56 (Fig. 8) to the work. With the supplementary reciprocating movement or displacement of 60 the tool which is characteristic of this process, any twisting between the tool and work would make its appearance through the play of the gears. This twisting is equalized by means of the apparatus now to be described. In order to 65 maintain simultaneity of the reversing motion and of the play equalizing means, both motions are caused by hydraulic pistons acting simultaneously.

The mechanism for equalizing the gear play is 70 illustrated in Fig. 8. The worm 55 of the dividing head worm gear 56 is mounted in bearings which are movable axially between adjustable limits. A casing 57 serving as an oil cylinder encloses a piston 58. Piston 58 is rigidly con- 75

nected to the worm shaft and the piston is displaceable between one wall of casing 57 as one limit, and the other cylinder wall 59 as the other limit. Wall 59 can be displaced by worms. The 5 displacement limits are adjusted in such manner that when the turning is taken into account, the tool is again in correct position with respect to the tooth spaces to be cut.

The slideway 12 is provided at one end with 10 an oil cylinder 60 (Figs. 9, 10 and 11). Piston 61 in this cylinder (Fig. 10) is subject to constant oil pressure at all times. Consequently, the carriage 14 is at all times held tightly against the threads of the nut and it is impossible for play 15 to be present in the threads.

The above-mentioned arrangement of the face-plate cylinder, swinging table guide and rotating parts on the table for producing the movements of the tool and work which are characteristic of this process, make it possible to give the tool any position desired for controlling its direction of movement in the crown gear plane, and to displace it forcibly in any desired direction over the face-plate. Therefore, not only is the machine 20 suitable for practicing the method just described, but in addition, it can also be used as a universal machine for generating teeth on spur gears and bevel gears according to other known rolling generating processes.

To this end, two different changeable rotating parts 16 (Fig. 10) and 16a (Figs. 9 and 11) can be used as tool supports and fixed on carriage 14 for this purpose. The difference between these tool supports is that the one 16a is arranged for 35 the reception of cylindrical cutters and the other 16 of cutters having conical or curved conical pitch surfaces.

The two changeable tool supports can, if desired, be equipped with grinding wheels instead 40 of cutters, for carrying out the process above described.

The work support 62 (Fig. 6) on which the work 4 is fixed to shaft 5, can be displaced vertically on a slideway 63. This movement is produced by actuation of worm spindle 64 in order 45 to cut teeth on bevel gears having displaced axes.

Adjustment of the slideway 63 is performed manually and its movement on a circular support 65 is guided radially with respect to its center of motion. The circular support 65 can be rotated 50 through an angle of ninety degrees about axis 66, to adjust the work so that its pitch line will lie in the common generating plane 66. This adjustment makes it possible to work bevel gears, spur gears, worms and numerous other similar work.

When spiral bevel gears are to be cut by cutters of the type shown in Fig. 1, the bevel gear 43 (Fig. 7) is connected to shaft 42 by coupling 60 41, thus throwing the dividing head out of gear. The shaft 42 is at the same time in driving relation with worm drive 55, 56 through change gears 45, 46 and 47. Hence, the work can make a continuous turn in correct relation to the rotation 65 of the tool. The slideway 12 is adjusted on the face plate to a position corresponding to that of the cutter and fixed. The pistons 67 and 61 (Figs. 6 and 10) are each under continuous equal pressures during the working process. Piston 67 70 forces the cutter case against the block gauges 68 or against stop spindle 69. The piston 61 in slideway 12, presses the nut in carriage 14 against the guide spindle 15 in order to compensate or eliminate play. At each change in direction of 75 tool movement the piston 17 in differential 18 is

reversed in order to give the cutter a movement in the direction of the arrow d. Piston 58 (Fig. 8) performs this same movement to correct the rotation of the dividing wheel.

When a cylindrical cutter is to be employed to 5 form the teeth of bevel gears, as shown in Fig. 2, the hydraulic pistons are driven in the same manner as for the tooth formation disclosed in Fig. 1. The only change required between the two methods is that for cone cutters the head 16 10 takes the form of Fig. 10, while for cylindrical cutters the head 16a has the form shown in Figs. 9 and 11.

When teeth are being cut with disk-shaped cutters, as shown in Figs. 3 and 5, the slideway 12 is fixed in position on the face-plate cylinder 11 and this position depends upon the curvature of the teeth which are being cut. Cylinder 17 on differential 18, and cylinders 60 and 67 are connected together by means of the regulating valve 20 referred to above. A continuous pressure is applied equally to both cylinders 60 and 67 during the whole tooth forming process. Oil pressure from pipe 70 acts on cylinder 67 to force the tool spindle 71 and cam 72 continuously against worm 25 spindle 69. This spindle can be adjusted by means of worm 73 and the block gauges 68 to regulate the depth of the teeth to be cut.

The oil pressure control valve is operated in accordance with the movement of carriage 14. 30 When the cutter has completed a tooth traverse in one direction, the oil supply to cylinder 17 is reversed and causes a reversal in the direction of cutter movement. The dividing device is also connected to the oil supply so that the hydraulic 35 motor 74 is under continuous pressure in one direction. Mechanism is also provided in connection with the regulating valve so as to control piston 58 and, at each stroke of the tool, correct any discrepancy in position between the tool and 40 work and caused by play in the gearing.

When a spiral cutter is to be used to generate spur gears, a cutter head of the type illustrated in Fig. 2 for use in forming bevel gears may be used, also the hydraulic pistons may be actuated 45 in the same manner as when generating bevel gears. However, the work support 65 is swung about the axis 66 in such a way that the axis of the work and the spindle 15 both lie parallel to the plane of face-plate 11.

In performing this adjustment, change gear 76 on spindle 75 at table 65 (Fig. 6) is brought into mesh with a change gear on shaft 77. Spindle 75 then serves to generate the feed motion in the direction of the work axis, as is usual in processes 55 of generating teeth on spur gears. With such a connection the shaft 77 is driven through gearing connecting it to shaft 78. Fixed on this worm shaft 78 is a coupling so arranged that worm 79 can be coupled to actuate the face-plate 60 cylinder 11 or to cause the gear 80 to drive the shaft 81, together with spindle 75 and shaft 78. The work 4 can be driven and feeding movement 65 imparted to the wheel in a direction along its axis by a connection which includes the differentials which have already been described.

The forward and reverse strokes of piston 17 for displacing the tool on slideway 12 in the direction of double arrow d, is transmitted to the 70 shaft 29 and then to the work through the second differential 18. The forward and reverse thrust of piston 17 effects the rotation of the case, the differential 18 and the gear 20. Rotary motion of the gear 20 is transmitted to lead screw 75

15 through gears 21, 22, 23 to 28, to move carriage 14 on slideway 12 in direction of arrow *d*.

The machine is so designed that it is capable not only of generating spur gear teeth in the manner just described, in which the work is moved along its own axis toward the tool, but it is also possible to guide the work tangentially to the tool. In this way, an additional advantage is obtained, namely, that each tooth on the tool 10 takes up as many tangential positions as desired, as its tangential cutting edge moves in the direction of tool feed. Therefore, any desired number of tangential cuts can be made, with the resulting increase in the accuracy of the tooth flanks.

15 Fig. 11 of the drawings illustrate the execution of the process just described. The work support 65 (see Fig. 6) is rotated about the axis 66 until the work axis is parallel to the plane of face-plate 11. However, the method of Fig. 11 differs 20 from that in Fig. 9 in that no feeding motion is imparted to the work support in Fig. 11.

The slideway 12 can be adjusted so that the tool moves tangentially along the dividing cylinder of the work, by rotating the face-plate 11. 25 The angle of inclination of the teeth to be generated is adjusted by swinging the cutter head inward. As shown in Fig. 11, the cutter is adjusted to produce tangential cuts, and the length of the cutter is so chosen that it extends over 30 the whole tooth width during the feeding movement, thus performing an additional back and forth movement. Thus it becomes possible to derive the tool movement for tool carriage 14 from a transmission operating solely on differential gear 50 and independently of differential gear 18. In Fig. 11, this tool movement is transmitted from differential worm shaft 31 over change gears 32 to 36, bevel gears 37, 38, spur gears 39, 24 to 26, bevel gears 21, 28 and along 35 spindle 16 to the tool carriage 14.

It is obvious that the machine can be arranged to carry out the tangential process in which the tool is fixed and the work is moved along the tool.

45 When bevel gear teeth are to be produced with longitudinally crowned teeth in which the crown is obtained by altering the milling depth, use may be made of a revolving cam 72 which serves as an eccentric. This cam is fixed to the housing 50 11 and is revolved back and forth through a definite angle of oscillation through change gears which cause the tool to be displaced in the direction of arrow *d* (Figs. 1, 2, 3 and 5). The entire housing 11 is, consequently, moved back 55 and forth in the direction of tooth depth. The adjustment and motion of the oscillating cam 72 has the following effect:

In position A of Fig. 3, the tool 1 is slightly 60 deeper than when at full tooth depth (full tool depth = 2.16 modul). In traveling to position B, the tool is drawn out of the tooth space until it takes the position B at normal tooth depth. In traveling from B to C, the tool again penetrates 65 deeper into the tooth space until it reaches the same depth as in position A. On the return travel from C to A, this same change in tooth depth occurs again.

The width between teeth changes with the 70 change in tooth depth, so that the tooth spaces become narrower in the center than at the ends. Consequently, when curved teeth are cut, the convex tooth flank has a sharper curvature than the concave tooth flank. The amount and rate of withdrawal and approach can be determined

in accordance with the point at which it is desired to crown the tooth.

Use of the machine above described assures absolute identity between pieces of work being cut. The hydraulic arrangement 67 presses the work spindle housing 11 against a stop which is adjustable by means of the block gauges 68 and the screw 69. This adjustment of the depth of cut by means of block gauges possesses marked advantages over prior art adjustments by threaded spindle and scale. The adjustment can now be carried out with accuracy by unskilled workmen and once the gauges are set, no further attention need be given to the adjustment.

What is claimed is:

1. A milling machine comprising a bed; an adjustable work support on said bed; a tool support on said bed; a main driving means for causing rotation of said work and tool supports; a first hydraulic means for imparting a supplementary rectilinear movement to said tool support; and a second hydraulic means connected to both said tool and work supports for eliminating lost motion therebetween.

2. A milling machine comprising a frame; an adjustable work support on said frame; means for rotating said support about the axis of the work gear; a face plate rotatable about the center of the imaginary face gear meshing with the gear being cut, said face plate having a slide thereon; a carriage on said slide; a rotatable tool support on said carriage; a tool on said tool support; means for causing reciprocatory movement of said carriage in a direction parallel to the cutting plane of the tool and in a direction substantially parallel to the axis of the tool; means for rotating the face plate and the tool thereon; and means for causing the reciprocatory movement of said carriage to take place in timed relation to the movement of the tool and work supports.

3. A milling machine comprising a frame; an adjustable work support on said frame; means for rotating said support about the axis of the work gear; a face plate rotatable about the axis 45 of the imaginary face gear meshing with the gear being cut; a rotatable tool support on said face plate, said support having a tool thereon; means for causing reciprocatory movement of said tool support in a direction parallel to the cutting plane of the tool and in a direction substantially parallel to the axis of the tool; means for rotating the face plate and the tool thereon; and means for causing the reciprocatory movement of the tool support to take place in timed 50 relation to the movement of the tool and work supports.

4. A milling machine comprising a frame; an adjustable work support on said frame; means for rotating said support about the axis of the work gear; a face plate rotatable about the center of the imaginary face gear meshing with the gear being cut, said face plate having a slide thereon; a carriage on said slide; a rotatable tool support on said carriage; a tool on said tool support; means comprising an hydraulic piston and transmission gearing for causing reciprocatory movement of said carriage in a direction parallel to the cutting plane of the tool and substantially parallel to the axis of the tool; means for rotating the face plate and the tool thereon; and means for causing the reciprocatory movement of said carriage to take place in timed relation to the movement of the tool and work supports.

5. A milling machine comprising a frame; an

adjustable work support on said frame; means for rotating said support about the axis of the work gear; a face plate rotatable about the axis of the imaginary face gear meshing with the gear being cut; a rotatable tool support on said face plate, said support having a tool thereon; means for causing reciprocatory movement of said tool support in a direction parallel to the cutting plane of the tool and substantially parallel to the axis of the tool; means for rotating the face plate and the tool thereon; and means interconnected with the means for rotating the face plate and work supports for causing the reciprocatory movement of the tool support to take place in timed relation to the movement of the tool and work supports.

6. A milling machine comprising a frame; an adjustable work support on said frame; means for rotating said support about the axis of the work gear; a face plate rotatable about the center of the imaginary face gear meshing with the gear being cut, said face plate having a slide thereon; a carriage on said slide; a rotatable tool support on said carriage; a tool on said tool support; means for causing reciprocatory movement of said carriage in a direction parallel to the cutting plane of the tool and in a direction substantially parallel to the axis of the tool; means for rotating the face plate and the tool thereon; means for causing the reciprocatory movement of said carriage to take place in timed relation to the movement of the tool and work supports; a cam; and means for actuating said cam in accordance with said reciprocatory movement for controlling the depth of cut of said tool.

7. A milling machine comprising a frame; a work support on said frame, said support being rotatable about the axis of the work gear; a face plate; means for rotating said face plate about the center of the imaginary face gear meshing with the gear being cut; a carriage on said face plate; a rotatable tool support on said carriage; a tool on said support; means effective during a milling operation of the machine to impart reciprocatory movement to said carriage in a direction substantially parallel to the axis of the tool and parallel to the cutting plane of the tool in

timed relation to the movement of said face plate to produce spiral bevel gears; and means for locking said face plate to cause tangential movement of the carriage and tool during a milling operation, whereby the machine may produce 5 spur gears.

8. A milling machine comprising a frame; a work support on said frame; said support being rotatable about the axis of the work gear; a face plate; means for rotating said face plate about 10 the center of the imaginary face gear meshing with the gear being cut; a carriage on said face plate; a rotatable tool support on said carriage; a tool on said support; means effective during a milling operation of the machine to impart reciprocatory movement to said carriage in timed 15 relation to the movement of said face plate, said movement being in a direction substantially parallel to the axis of the tool and parallel to its cutting plane; a dividing mechanism operatively 20 connected with said tool support; and means for connecting and disconnecting said dividing mechanism and said tool support.

9. A milling machine comprising a frame; a work support on said frame; said support being 25 rotatable about the axis of the work gear; a face plate; means for rotating said face plate about the center of the imaginary face gear meshing with the gear being cut; a carriage on said face plate; a rotatable tool support on said carriage; 30 a tool on said support; means effective during a milling operation of the machine to impart reciprocatory movement to said carriage in a direction parallel to the cutting plane of the tool and substantially parallel to the axis of the tool in 35 timed relation to the movement of said face plate; a housing for the tool support; hydraulic means for displacing said housing against said tool support; a rotatable cam between said housing and said displacing means, said cam being 40 effective to change the depth of cut during a cutting operation without stopping the machine; and means comprising at least one block gauge for gauging the total depth of cut made by the machine.
